[57] CLAIM

The ornamental design for a combined desk top and base, as shown and described.

DESCRIPTION

FIG. 1 is a perspective view of a combined desk top and base showing my new design;

FIG. 2 is a top plan view of the top;

FIG. 3 is a bottom plan view of FIG. 1;

FIG. 4 is a front elevational view thereof;

FIG. 5 is a rear elevational view thereof;

FIG. 6 is a left side elevational view thereof; and,

FIG. 7 is a right side elevational view thereof.

The portions of the desk shown in broken lines are for illustrative purposes only and forms no part of the claimed design.
